UNITED STATES PATENT OFFICE

143,106

DESIGN FOR A COMBINED CLOCK AND DOOR CHIME

Nathan Abramson, New York, N. Y., assignor to
Presto Electric Co., Union City, N. J., a partnership

Application October 6, 1944, Serial No. 115,647

Term of patent 7 years

(Cl. D42—7)

To all whom it may concern:

Be it known that I, Nathan Abramson, a citizen of the United States of America, residing at New York 17, in the county and State of New York, have invented a new, original, and ornamental Design for a Combined Clock and Door Chime, of which the following is a specification, reference being had to the accompanying drawing, forming part hereof.

Referring to the drawing:

Figure 1 is a front perspective view of a com-

bined clock and door chime showing my new design;

Figure 2 is a side elevational view taken from the left-hand side of Figure 1; and

Figure 3 is a top plan view, the back and the side not shown, being plain.

I claim:

The ornamental design for a combined clock and door chime, as shown and described.

NATHAN ABRAMSON,
